UNITED STATES PATENT OFFICE.

CHARLES W. SHERBURNE, OF BOSTON, MASSACHUSETTS, ASSIGNOR TO THE AMERICAN LOCOMOTIVE SANDER COMPANY, OF PHILADELPHIA, PENNSYLVANIA.

TRACK-SANDING DEVICE.

SPECIFICATION forming part of Letters Patent No. 665,138, dated January 1, 1901.

Application filed September 14, 1900. Serial No. 30,016. (No model.)

To all whom it may concern:

Be it known that I, CHARLES W. SHERBURNE, a citizen of the United States, residing at Boston, in the county of Suffolk and

5 State of Massachusetts, have invented a new and useful Improvement in Track-Sanding Devices, of which the following is a full, clear, and exact description, reference being had to the accompanying drawings, forming a part 10 of this specification, in explaining its nature.

The invention consists in providing in the base of a locomotive sand-dome or other similar sand-holding vessel air and sand feeding passages, preferably formed in the act of casting the base of the dome and extending inward from the edge of the dome and which are adapted one to contain an air-supply pipe and the other to be connected with a sand-delivery pipe, both of which are attachable to 15 the base in line with said passages and from the outside of the dome or vessel.

The invention will be described in detail in connection with the drawings, wherein—

Figure 1 is a view, principally in plan, of 25 enough of the base of a sand-dome to illustrate the features of the invention. Fig. 2 is a view largely in vertical section upon the dotted line 2 of Fig. 1. Figs. 3, 4, 5, and 6 illustrate slight modifications in the arrangement 30 of the passages, to which reference will hereinafter be made.

A is the base of the sand-dome. In Fig. 1 it is represented as provided with the horizontal passage B, extending from its outer 35 edge b inward to the point b', from which extends diagonally toward the outer edge of the base the return-passage b², which opens into an inclined passage b³, having an outlet b⁴ into the sand-delivery pipe b⁵ and inlet b⁶, 40 adapted to be covered and uncovered by the hand-operated valve C, contained in the chamber of the sand-dome. The inner end of the passage b' is connected with the sand-holding chamber of the sand-dome by the vertical 45 opening or passage b⁷. In the horizontal passage B there is arranged an air-supply pipe D, one end of which extends outward through the casing of the dome and is connected, by 50 means of a coupling or in any other manner, 50 with an air-supply pipe d, running from a source of air-supply, such as the air-reservoir

of the Westinghouse air-brake. The inner end of the air-supply pipe D is turned backward beneath the hole b⁷ and so that its outlet b⁸ will discharge into the passage b². 55

The operation of the device is as follows: Sand from the chamber of the dome feeds through the hole b⁷ to a position in front of the outlet of the air-supply pipe, and the air discharged from the end of said pipe forces it 60 along the horizontal pipe b² into the passage b³ to the sand-delivery pipe, by which it is fed to the rails. The sand from the dome-chamber both feeds by gravity and is drawn to a position in front of the outlet of the air-supply pipe; 65 but it is not fed through the passage b² by gravity, as the said passage is horizontal and long. To obtain a gravity hand-feed, the valve C is used, and it is adapted to cover and uncover the opening b⁶ of the passage b³ to the sand-delivery pipe, and the pipe b³ is so inclined 70 that upon the opening of the valve C sand will fall from the chamber of the dome through it into the sand-delivery pipe. The air-delivery pipe D is attached to the base of the dome by 75 means of a threaded holder E, which screws from outside of the dome into the threaded end e of said passage B. This permits the air-pipe to be readily attached from outside the dome and also to be as readily removed, 80 if desired. The sand-delivery pipe b⁵ is united to the base from outside the dome by screwing into the threaded lower end of the vertical passage b³. In Figs. 3 and 4 the passage B extends from the outer side of the dome directly to the passage b³. The hole b⁷, connecting the chamber of the dome with the passage, 85 is arranged about midway its length. The section of the passage to the hole is the equivalent of the passage B of Figs. 1 and 2 and 90 the section from the hole to the passage b³ is the equivalent of the passage b² of Figs. 1 and 2. In this modification the inner end of the air-supply pipe is not bent. In Figs. 5 and 6 I have represented the passage for the air-supply pipe as extended across the passage b³ and as provided with a return-section from 95 its inner end to said passage. The hole for connecting the chamber of the dome with it is located at its inner end, and it is enlarged 100 from its inner end to the passage b³ to provide a channel through which the sand is fed by

the air to the sand-delivery pipe. The equivalent of the passage b^2 is found in the return-section from the inner end of the passage to the entrance to the passage b^3 .

5 Among the principal advantages of the invention are those which arise from the cheapness with which the invention may be applied to the sand-dome and engine and the various passages reached from outside the dome 10 for the purpose of cleaning them and freeing them from obstructions.

Having thus fully described my invention, I claim and desire to secure by Letters Patent of the United States—

- 15 1. In a track-sanding apparatus, a sand-dome having a base provided with passages extending inward from the edge of the base and connected with each other within the base, both of which are connected by vertical 20 holes with the sand-holding chamber, a hand-operated valve for controlling the one of said holes which connects directly with the sand-distributing pipe and an air-supply pipe contained in the other with its outlet beneath the 25 hole connecting it with said chamber and arranged to blow or force the sand to the sand-

delivery pipe and the said air-supply pipe attachable to the base from the outer side thereof.

2. The combination in a track-sanding apparatus, of a dome having a metal base, the passages B b^3 formed in the base by casting or otherwise, extending from the outer edge of said base inward and connected at their inner ends, said hole b^3 being inclined, the 30 hole or inlet b^6 connecting the sand-holding chamber with the inner end of the said passage b^3 , the hole or opening b^7 connecting the sand-holding chamber with the passage B , a hand-operated valve for controlling the inlet 40 b^6 , an air-supply pipe extending from the outer side of the base through the passage B and ending below the hole or opening b^7 , the portion of the passage or connection between the holes b^7 and b^6 being substantially horizontal, 45 and the sand-delivery pipe and the air-supply pipe attached to the outer edge of the base or dome.

CHARLES W. SHERBURNE.

In presence of—

GEORGE O. G. COALE,
J. M. DOLAN.
